(57) CLAIM

The ornamental design for a spout, as shown and described.

DESCRIPTION

FIG. 1 is a perspective view of the new design for a spout; FIG. 2 is a front elevational view of the new design for a spout;

FIG. 3 is a rear elevational view of the new design for a spout;

FIG. 4 is a right side elevational view of the new design for a spout, the left side elevational view being a mirror image; FIG. 5 is a top plan view of the new design for a spout; and, FIG. 6 is a bottom plan view of the new design for a spout. The broken lines in the Figures are for illustrative purposes only and form no part of the claimed design.
